UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

ROCK-DRILLING MECHANISM.

Application filed December 26, 1922. Serial No. 609,128.

My invention relates to rock drilling mechanisms, and more particularly to improved controlling and feeding mechanisms for such drilling mechanisms.

5 An object of my invention is to provide an improved rock drilling mechanism. Another object of my invention is to provide an improved controlling mechanism for rock drilling mechanisms, and more particularly 10 an improved controlling mechanism for drilling mechanisms of the so-called "stoper" type. A further object of my invention is to provide an improved and simplified fluid supply connection and controlling mechanism for rock drilling mechanisms. Other 15 objects and advantages of my invention will hereinafter more fully appear.

In the accompanying drawings I have shown for purposes of illustration two 20 forms which my invention may assume in practice, the same being illustrated as applied to stopers.

In these drawings,—

25 Fig. 1 is a view partially in elevation and partially broken away, showing a drilling mechanism embodying my improved construction.

Fig. 2 is a view mainly in vertical central section through one form of my improved 30 fluid supply connection and controlling mechanism.

Fig. 3 is a similar view through a modified construction.

Fig. 4 is a detailed section on the line 35 4—4 of Fig. 3.

Fig. 5 is a central longitudinal sectional view taken on line 5—5 of Fig. 1.

Fig. 6 is a detail sectional view taken on line 6—6 of Fig. 2.

40 In the first illustrative form I have shown at 1 a drill of the so-called stoper type comprising a drilling motor 2 in whose cylinder 3 a piston 4 is reciprocable, this piston having a forwardly projecting striking bar 45 4^a which percussively actuates through a striking plug 5^a a drill steel 5 in a well known manner. Associated with the motor and operative to feed it toward the work under the control of improved controlling 50 mechanism, hereinafter described, is a feeding mechanism generally designated 6 and including a feed cylinder 7 arranged in fixed relation to the motor 2 and enclosing in its bore 8 a piston 9 whose piston rod 10

is provided with an abutment engaging point 55 11 so that during the operation of the motor said piston may remain stationary and said feed cylinder 7 and motor 2 may be fed toward the work.

Projecting laterally from the drilling mechanism and herein carried by an intermediate block 12, although other positions might be selected, is a handle 13 which serves to conduct through the passages 14 and 15 therein fluid respectively through distribution passages 14^a to operate the motor 2 and through a passage 15^a to effect feeding of the motor toward the work. This handle is employed to enable the drilling mechanism to be bodily oscillated about the axis of the drill steel and in case the latter sticks in the hole and to facilitate the support of the mechanism. It will herein be noted that the motor cylinder 2, intermediate block 12, and the feed cylinder 7 are held in assembled relation by means of usual side rods 12^a 70 in a well known manner. At the end of the handle member 13 is arranged, with its axis at right angles thereto, a valve casing 16 which has a conical bore 17 in which a valve member 18 is rotatably disposed. At the lower end of the member 16 and screwed into the bore of the latter at 19 is a connection 20 for motive fluid supply, a strainer 21 being arranged between this connection 75 and the valve member 18. The latter has a hollow bore 22 which communicates, by way of a lateral port 23, in certain positions of the valve with the motor supply connection 14. A passage 24 also extends axially of the valve and communicates with a slightly enlarged chamber 25 at whose lower end a valve seat 26 surrounds the passage 24. A lateral port 27 opening into a circumferentially extending groove 28 serves to permit supply of fluid when the valve 18 is in proper angular position to the passage 15. It will herein be observed that a groove 27^a 85 and a vent port 28^a are provided in the valve 18 and the casing 16 respectively and when this groove is brought into communication with the vent port the feed cylinder is vented to atmosphere in a usual manner. Reciprocable in the chamber 25 is a valve member 29 normally held open by a spring 30 90 engaged a collar 31 secured to the stem 32 of the valve member 29. A push button 33 95 is arranged at the upper end of the stem 32 100

105 of the valve member 29. A push button 33 110 is arranged at the upper end of the stem 32

so that the valve 29 may be readily forced to closed position. Surrounding the stem 32 is a manual grasping handle 34 which is held at 35 to a boss 36 arranged at the upper 5 end of the valve member 18. It will be evident that by rotation of the handle portion 34 the valve 18 may be rotated. When air pressure is on, the valve is forced up into the conical bore which causes the valve to 10 resist accidental turning.

The mode of operation of this form of my invention will be readily apparent. When it is desired to operate the drilling mechanism, the operator will bring the same 15 into the desired position and place the abutment point 11 against some suitable solid support. He will next rotate the handle portion 34 in such manner as to open communication between the groove 28 and the 20 passage 15, and the port 23 and the passage 14. In order to prevent the pressing of the drill with excessive force against the rock during spotting of the hole, the button 33 may be depressed, partially or wholly closing 25 communication between the passage 24 and the passage 27. After the hole is started, by suitably depressing and releasing the push button 33, the valve 29 may be so moved as to control the supply of fluid to the 30 feeding mechanism through the port 15 at such rate as to provide any desired force of feed.

In Figures 3 and 4 I have shown another form which my invention may assume in 35 practice. In most particulars this form of my invention closely resembles that just described. However, in certain particulars it differs therefrom. It will be noted that the end of the valve casing 16' communicates 40 with the passage 14 and that the fluid admission takes place through a line 20' opening laterally into the interior of a valve member 18' so that supply of fluid to the motor is controlled by the bringing of a 45 port 23' into communication with the line 20' and the flow of fluid through the valve is, so to speak, reversed. The general arrangement of the valve 29' which corresponds to the valve 29 is the same as in the 50 preceding described form of my invention. The connection, however, to the port 15 is somewhat different, the port 27' communicating with a passage 37 which extends longitudinally through the wall of the valve 55 casing 16'. This passage 37 opens through a passage 38 into communication with the passage 15. In this form of my invention the valve 29' is operated by a lever 40 which is drawn toward a handle 41 extending at 60 right angles to the handle 13 in order to close the valve 29'. A lug 42 on the handle 41 is adapted to engage a stop 43 on the valve casing 16' when the valve 18' is in full open position.

65 It is believed that it is unnecessary to de-

scribe the mode of operation of this mechanism other than to say that by rotation of the handle 41 the port 23' is brought into communication with the inlet 20' and the port 27' is brought into communication with the passage 37, while by operation of the handle 40 the position of the valve 29' may be varied to control the force of the feed.

70 While I have in this application specifically described two forms which my invention may assume in practice, it will be understood that these forms of the same are shown for purposes of illustration and that the invention may be modified and embodied in other forms without departing from 80 its spirit or the scope of the appended claims.

What I claim as new and desire to secure by Letters Patent is:

1. In a drilling mechanism, the combination with a drilling motor, feeding means 85 therefor, and a manual grasping handle projecting laterally at one side of the drill, of means for controlling the operation of both said motor and said feeding means including ports and passages permitting the passage of motive fluid through the handle to said drilling motor and feeding means, and controlling mechanism for enabling the operator to control the flow of fluid through said ports and passages, said mechanism being arranged wholly at the outer extremity 90 of said handle.

2. In a rock drilling mechanism, a fluid pressure operated percussive motor and fluid operated feeding means, a laterally projecting handle extending from said mechanism, and relatively movable valves for controlling the motor and the feed arranged wholly at the outer extremity of said handle.

3. In a rock drilling mechanism, a fluid 105 pressure operated percussive motor and fluid operated feeding means, a laterally projecting supporting handle extending from said mechanism, and a fluid supply connection and fluid controlling means arranged wholly 110 at the outer extremity of said handle.

4. In a rock drilling mechanism, a fluid pressure operated percussive motor and fluid operated feeding means, a laterally projecting supporting handle extending from said 115 mechanism, and separately operable valves for controlling the motor and the feed and a fluid supply connection arranged wholly at the outer extremity of said handle.

5. In a rock drilling mechanism, a percussive drilling motor, fluid operated feeding means, and fluid supply connections for said motor and feeding means including a laterally projecting supporting handle and controlling valve means for said motor and feeding means having concentric operating handles at the outer extremity of said first mentioned handle.

6. In a rock drilling mechanism, in combination, a fluid operated drilling motor, a 130

fluid operated feed, a laterally projecting supporting handle, and means arranged wholly at the outer extremity of said handle and including a fluid supply connection, and 5 a plurality of valves for supplying a controlled quantity of fluid pressure to said motor and feed. 70

7. In a rock drilling mechanism, in combination, a fluid operated drilling motor, a 10 fluid operated feed, a laterally projecting supporting handle, and means arranged wholly at the outer extremity of said handle and including a fluid supply connection, and a plurality of valves for supplying a controlled quantity of fluid pressure to said 15 motor and feed, said valve means having operating devices lying in a common plane with said fluid supply connection. 80

8. A drilling mechanism comprising a 20 drilling motor and fluid actuated feeding means therefor, a supporting handle projecting laterally from said mechanism having an angular portion thereon adapted to be grasped by the operator, and means carried by said angular portion for controlling the motive fluid supply to said drilling motor. 85

9. A drilling mechanism comprising a 30 drilling motor and fluid actuated feeding means therefor, a supporting handle projecting laterally from said mechanism having an angular portion thereon adapted to be grasped by the operator, and means including controlling elements carried by said 35 angular portion for controlling the fluid supply to said drilling motor and to said feeding means. 90

10. A drilling mechanism comprising a 40 drilling motor adapted to actuate a tool and pressure fluid feeding means therefor, a supporting handle means for rotating the tool, a throttle valve mounted on said supporting handle and provided with a handle adapted to be grasped by the operator for 45 controlling the pressure fluid supply to said motor and to said feeding means, and means enabling the operator to control the rotation and said feeding means by but a single hand without removing said hand from said throttle valve controlling handle. 100 105

11. In a drilling mechanism, a fluid actuated drilling motor, a fluid actuated feeding means therefor, a supporting handle projecting from said mechanism adapted to be grasped by the operator, and means for controlling the fluid supply to said drilling motor and to said feeding means including controlling means for both of the latter arranged at the extremity of 60 said handle. 110

12. A drilling mechanism comprising a 65 fluid actuated drilling motor and fluid actuated feeding means therefor, a supporting handle projecting laterally from said mechanism a substantial distance to provide 115

leverage adapted to be grasped by the operator, and means operable from said handle for enabling the operator to control the fluid supply to said drilling motor by but a single hand without removing said hand 70 from said handle. 120

13. A drilling mechanism comprising a drilling motor and feeding means therefor, a rotation handle projecting from said mechanism adapted to be grasped by the operator, and means enabling the operator to control said drilling motor, said feeding means, and the rotation by but a single hand without removing said hand from said handle. 75 80

14. A drilling mechanism comprising a drilling motor adapted to actuate a tool and feeding means therefor, a supporting handle means for rotating the tool, and means including a common element mounted on said supporting handle for enabling the operator to control said drilling motor, said feeding means, and the rotation. 85

15. A drilling mechanism comprising a drilling motor adapted to actuate a tool and feeding means therefor, a supporting handle member means for rotating the tool, a controlling means for said motor provided with a handle at the end of said supporting member adapted to be grasped by the operator, 90 and means enabling the operator to control the drilling motor and the rotation with but a single hand without removing said hand from said handle. 95

16. A drilling mechanism comprising a work performing means and feeding means therefor, means extending from said mechanism a substantial distance to provide leverage adapted to be grasped by the operator and means including coaxial valves and a reciprocable operating element for enabling the operator to control said work performing means and said feeding means by but a single hand without removing said hand from said grasping means. 100 105 110

17. A drilling mechanism comprising a work performing means and feeding means therefor, means extending from said mechanism a substantial distance to provide leverage adapted to be grasped by the operator, means including coaxial valves and a reciprocable operating element for enabling the operator to control said work performing means and said feeding means by but a single hand without removing said hand from said grasping means, and a fluid supply connection arranged adjacent said valves. 115 120

18. A drilling mechanism comprising a drilling motor and fluid actuated feeding means therefor, a rotation arm extending laterally from said mechanism and carried thereby, and a valve having an operating handle and carried by said arm for controlling said mechanism, said handle also constituting 125 130

tuting a handle for said arm which may be normally grasped to cause rotation of said mechanism.

19. A drilling mechanism comprising a drilling motor and fluid actuated feeding means therefor, a rotation arm extending laterally from said mechanism and carried thereby, and a valve having an operating handle angularly disposed to the longitudinal axis of said arm and carried thereby for controlling said mechanism, said handle also constituting a handle for said arm which may be normally grasped to cause rotation of said mechanism.

15 20. A drilling mechanism comprising a drilling motor and feeding means therefor, a rotation arm extending laterally from said mechanism and carried thereby, and a valve having an operating handle and carried by the outermost end of said arm for controlling said mechanism, said handle also constituting a handle for said arm which may be normally grasped to cause rotation of said mechanism.

20 25. A drilling mechanism comprising a drilling motor and fluid actuated feeding means therefor, a rotation arm extending laterally from said mechanism including a

valve housing parallel to said feeding means, and a valve disposed within said housing and having a handle, said handle constituting a means whereby rotation can be imparted to said mechanism through said valve. 30

22. In a drilling mechanism, the combination with a fluid actuated drilling motor, fluid actuated feeding means therefor, and a drill supporting handle extending laterally at one side of the drill, of motor and feed controlling means comprising ports and passages permitting the flow of fluid through 35 said handle to said motor and feeding means, a valve located in said handle, said valve having means for enabling the operator to control the flow of fluid through the handle, and an operating member for said valve arranged at the outer extremity of said handle. 40

23. In a rock drilling mechanism, a fluid actuated drilling motor, fluid actuated feeding means therefor, a laterally projecting handle extending from said mechanism, and means for controlling said drilling motor and feeding means carried at the outer extremity of said handle. 45 50

In testimony whereof I affix my signature.

CHARLES F. OSGOOD.

tuting a handle for said arm which may be normally grasped to cause rotation of said mechanism.

19. A drilling mechanism comprising a drilling motor and fluid actuated feeding means therefor, a rotation arm extending laterally from said mechanism and carried thereby, and a valve having an operating handle angularly disposed to the longitudinal axis of said arm and carried thereby for controlling said mechanism, said handle also constituting a handle for said arm which may be normally grasped to cause rotation of said mechanism.
- 15 20. A drilling mechanism comprising a drilling motor and feeding means therefor, a rotation arm extending laterally from said mechanism and carried thereby, and a valve having an operating handle and carried by the outermost end of said arm for controlling said mechanism, said handle also constituting a handle for said arm which may be normally grasped to cause rotation of said mechanism.
- 20 25. A drilling mechanism comprising a drilling motor and fluid actuated feeding means therefor, a rotation arm extending laterally from said mechanism including a

valve housing parallel to said feeding means, and a valve disposed within said housing and having a handle, said handle constituting a means whereby rotation can be imparted to said mechanism through said valve.

22. In a drilling mechanism, the combination with a fluid actuated drilling motor, fluid actuated feeding means therefor, and a drill supporting handle extending laterally at one side of the drill, of motor and feed controlling means comprising ports and passages permitting the flow of fluid through said handle to said motor and feeding means, a valve located in said handle, said valve having means for enabling the operator to control the flow of fluid through the handle, and an operating member for said valve arranged at the outer extremity of said handle.

23. In a rock drilling mechanism, a fluid actuated drilling motor, fluid actuated feeding means therefor, a laterally projecting handle extending from said mechanism, and means for controlling said drilling motor and feeding means carried at the outer extremity of said handle.

In testimony whereof I affix my signature.

CHARLES F. OSGOOD.

CERTIFICATE OF CORRECTION.

Patent No. 1,641,451.

Granted September 6, 1927, to

CHARLES F. OSGOOD.

It is hereby certified that error appears in the printed specification of the above numbered patent requiring correction as follows: Page 1, line 71, strike out the word "and"; page 3, line 41, claim 10, and line 83, claim 14, after the word "handle" insert a comma; same page, line 92, claim 15, after the word "member" insert a comma, and line 94, after the word "supporting" insert the word "handle", line 104, claim 16, after the word "operator" insert a comma; and that the said Letters Patent should be read with these corrections therein that the same may conform to the record of the case in the Patent Office.

Signed and sealed this 1st day of November, A. D. 1927.

Seal.

M. J. Moore,
Acting Commissioner of Patents.
